G. C. DEVITT & S. B. WHISTLER,
BEARING FOR SCALES,
APPLICATION FILED AUG. 16, 1915.

1,245,202.

Patented Nov. 6, 1917.

UNITED STATES PATENT OFFICE.

GEORGE C. DEVITT AND SANFORD B. WHISTLER, OF BUFFALO, NEW YORK, ASSIGNEES
TO BUFFALO SCALE COMPANY, OF BUFFALO, NEW YORK, A CORPORATION OF NEW
YORK.

BEARING FOR SCALES.

1,245,202.

Specification of Letters Patent.

Patented Nov. 6, 1917.

Application filed August 16, 1915. Serial No. 45,645.

To all whom it may concern:

Be it known that we, GEORGE C. DEVITT and SANFORD B. WHISTLER, citizens of the United States, residing at Buffalo, in the 5 county of Erie and State of New York, have invented new and useful Improvements in Bearings for Scales, of which the following is a specification.

This invention relates to bearings for 10 scales and more particularly to bearings for this purpose which are provided with anti-friction means for preventing undue frictional contact between two scale members adjacent to the pivotal connection between 15 the same.

The object of this invention is to provide 20 an improved bearing of this character which is simple and inexpensive in construction and reliable in operation and which is provided with an anti-friction device of simple and efficient construction which can be readily applied to or removed from the bearing so that the same can be renewed when worn and which permits of reducing 25 the frictional contact between two relatively movable scale members either on one side of the bearing or on opposite sides thereof.

In the accompanying drawings: Figure 1 30 is a side elevation, partly in section, of a platform scale provided with bearings constructed in accordance with our invention. Fig. 2 is a cross section thereof, on an enlarged scale, taken on line 2—2, 35 Fig. 1. Fig. 3 is a perspective view of one form of scale bearing embodying our invention. Fig. 4 is a vertical longitudinal section of the same. Fig. 5 is a vertical transverse section of the same. Fig. 6 is 40 a perspective view of the anti-friction device applied to the bearing. Fig. 7 is a fragmentary longitudinal section showing our improved bearing applied to a form of scale lever different from that shown in Figs. 1 and 2. Fig. 8 is an end view of the construction shown in Fig. 7.

Similar characters of reference indicate corresponding parts throughout the several views.

Our improved bearing is applicable to 50 various kinds of scales but as shown in the drawings the same is applied to a platform scale which consists essentially of a hollow main frame or base 1 which is provided 55 with an opening in its top, a platform 2

arranged above the frame and provided with legs 3 on its underside which project downwardly through the opening in the frame and two overlapping levers 4, 5 arranged within the frame and forming part of 60 the means whereby the platform is movably supported and the movement of the platform is transmitted to the scale beam in the usual and well known manner. These levers may be pivotally connected with each 65 other by any suitable means, for instance by a coupling ring 6 engaging with a pivot pin 7 on the toe of the short lever 4 and a pivot pin 8 on the central part of the long lever 5. Intermediate of their ends these 70 levers pivotally support the platform by providing these portions of these levers with pivot pins 9 engaging with bearing blocks 10 mounted on the lower ends of the platform legs, as shown in Fig. 1. 75

Our improved bearing and anti-friction device is embodied in this scale for pivotally supporting these levers at the heels thereof, at which places these levers are provided with the usual knife edge pivot 80 pins 11.

Our improved bearing and friction device may be variously organized and still accomplish the purpose for which the same is designed but in its preferred form each 85 of these bearings, as shown in the drawings, is constructed as follows:

12, 12 represent two side pieces or cheeks which are preferably constructed of sheet metal and each of which is provided with 90 an opening so as to form two upright side bars 13 a lower cross bar 14 connecting the lower ends of the side bars and an upper cross bar 15 connecting the upper ends of the side bars. At the lower end of each 95 opening of the side piece the same is provided with a flat horizontal seat 16, and about midway of their height the side bars are provided with inwardly projecting lugs forming downwardly facing shoulders 17. 100 These side pieces are arranged vertically and parallel with each other and the same are connected below their bearing openings by means of a lower longitudinal connecting member 18 and above the bearing openings by means of an upper connecting member 19, which connecting members, as shown in the drawings may consist of rivets, but if desired they may be made of any other suitable form. These side pieces and the 110

connecting rivets form the frame of the bearing and the same is supported on the main frame of this scale by means of a link or loop 20 the lower end of which receives 5 the upper connecting rivet 19 of the frame between the side pieces while its upper end receives a supporting pin 21 mounted on the upper part of the main frame, as shown in Figs. 1 and 2.

10 22 represents the bearing block which is arranged with its opposite ends in the lower part of the bearing openings of the side pieces and is provided with a flat underside while its upper side is provided with a V-shaped bearing face which engages with the knife edge of the companion pivot pin extending lengthwise through the upper part of the bearing opening of the side pieces. The shoulders 17 of the side pieces of the 15 frame project inwardly over the upper longitudinal corners of the bearing block so as to hold the latter against vertical displacement and the longitudinal sides of the bearing block are confined against lateral 20 displacement between the lower parts of the side bars of the side pieces. The bearing block is fitted comparatively loose in this part of the bearing frame so that the same is capable of a limited oscillation in a trans- 25 verse direction relatively to the bearing frame in order to enable the bearing block to adapt itself freely to the shifting of its companion pivot pin when the scale is in use and thereby avoid interfering with the 30 sensitiveness in the operation of the scale.

The bearing block is held against longitudinal displacement in the bearing frame by means of a key which is preferably constructed of two sections which for convenience and cheapness of manufacture are 35 preferably punched out of sheet metal and which are constructed to form two lower eye sections 23, 23 and two upper locking tongue sections 24, 24. The sections of this 40 key are placed with their eyes between the lower cross bars of the frame side pieces so that the lower connecting rivet 18 passes through these eyes and the tongue sections thereof project upwardly above this lower 45 cross piece and into a locking recess or opening 25 formed in the underside of the bearing block, as shown in Figs. 4 and 5. By this means the bearing block is interlocked with the frame so that the same cannot move 50 in a direction lengthwise of its bearing face and the pivot pin with which the same co- 55 operates.

The anti-friction device which is associated with this bearing, in its preferred 60 form, is constructed as follows:

26 represents the body of the anti-friction device which is preferably constructed in the form of a plate and arranged between the underside of the bearing block and the 65 seats 16 on the upper side of the lower frame

cross bars. At its opposite ends this body plate is provided with two bearing lips 27 which project laterally across opposite ends of the bearing block, and on the outer side of each of these lips the same is provided with a bearing nose 28 which projects outwardly in a direction lengthwise of the bearing face of the block and the companion pivot pin. The central part of the body plate is provided with an opening 29 which 70 coincides with the opening or recess of the bearing block and the locking tongue sections which enter the openings of the bearing block also project through the opening of the body plate. The key therefore operates as means for retaining the anti-friction device against longitudinal displacement between the bearing frame and bearing block which operation is also performed by the lips of the anti-friction device engaging 75 with opposite ends of the bearing block. This anti-friction device is preferably constructed from a single piece of sheet metal, such as steel, so as to render the same cheap, strong and durable. When this bearing is 80 utilized in connection with a pivot pin which projects laterally from one side only of a scale lever only one nose of the anti-friction device engages with the opposing surface of this lever for the purpose of reducing the 85 frictional contact between adjacent relatively movable parts of the scale, as shown in Figs. 1 and 2.

But if this anti-friction device is used in a bearing which has its block engaging 90 with a pivot pin 30 supported at its opposite ends by the arms 32, 32 of a bifurcated lever 31, as shown in Figs. 7 and 8, both bearing noses of the anti-friction device engage with the inner sides of the bifurcated 95 portions of the last mentioned lever and reduce the frictional contact between the same and the bearing.

In practice it is desirable to construct the anti-friction device in all cases with two 100 bearing noses which are arranged on opposite sides of the bearing regardless of whether the same is to be used on a scale having pivots which are supported only at one end as well as pivots which are supported at opposite ends, inasmuch as this 105 permits of a uniformity of construction and avoids the necessity of exercising any particular care when assembling the parts of the scale as to whether or not one end or the 110 other of the bearing faces the opposing side of the scale lever, thereby effecting a saving 115 in time and a reduction in the cost of putting up the scales.

Our improved scale bearing and anti-friction device can be produced at comparatively low cost. The same is very strong and not liable to get out of order and when the noses of the anti-friction device become worn 120 this device can be readily replaced by a new 125 130

one for the purpose of maintaining the accuracy of the scale.

We claim as our invention:

1. A bearing for scales comprising a frame having two side pieces each of which is provided with an opening one end of which forms a seat and also provided with internal shoulders which face said seat, a bearing block arranged at its opposite ends in the openings of said side pieces and engaging at its rear side with the seats thereof and at its front side with said shoulders, and means for holding said block against lengthwise movement in said side pieces. 5
2. A bearing for scales comprising a frame having two side pieces each of which is provided with an opening one end of which forms a seat and also provided with internal shoulders which face said seat, a bearing block arranged at its opposite ends in the openings of said side pieces and engaging at its rear side with the seats thereof and at its front side with said shoulders, and means for holding said block against lengthwise movement in said side pieces comprising a key mounted on the side pieces and engaging with a recess in the rear side of said bearing block. 10
3. A bearing for scales comprising a frame having two side pieces each of which is provided with an opening one end of which forms a seat and also provided with internal shoulders which face said seat, a bearing block arranged at its opposite ends in the openings of said side pieces and engaging at its rear side with the seats thereof and at its front side with said shoulders, said block being also provided on its rear side with a recess, a rivet connecting said side pieces in the rear of said block, and a key having an eye mounted on said rivet and provided with a tongue engaging said recess in said block. 15
4. A bearing for scales comprising a frame, a bearing block mounted on said frame and adapted to engage with a pivot pin of the scale, and an anti-friction device comprising a body plate arranged between the back of said block and the adjacent part of said frame, a lip arranged on the end of said body plate and extending across the end of said block, and a bearing nose projecting laterally from said lip and adapted to engage an adjacent member of the scale. 20
5. A bearing for scales comprising a frame, a bearing block mounted on said frame and adapted to engage with a pivot pin of the scale, and an anti-friction device comprising a body plate arranged between the back of said block and the adjacent part of said frame, lips arranged on opposite ends of said body plate and extending across the opposite ends of said block, and bearing noses arranged on said lips and projecting laterally therefrom. 25
6. A bearing for scales comprising a frame, a bearing block mounted on said frame and adapted to engage with a pivot pin of the scale, and an anti-friction device comprising a body plate arranged between the back of said block and the adjacent part of said frame, said block and body plate being provided with coinciding openings, a lip arranged on the end of said body plate and extending across the end of said block, a bearing nose arranged on said lip and projecting laterally therefrom and adapted to engage an adjacent member of the scale, and a key mounted on the frame and engaging with said openings. 30
7. A bearing for scales comprising a frame having two side pieces each of which has an opening forming a seat and front and rear rivets connecting said side pieces in front and in rear of said openings, a bearing block arranged in the openings of said side pieces and having a front bearing face adapted to engage a pivot pin of the scale and provided on its rear side with a locking opening, an anti-friction device having a body-plate arranged between said seats and the rear side of the block and provided with an opening, lips arranged on the ends of said body plate and extending across the ends of said block and noses arranged on said lips and projecting laterally therefrom and adapted to engage an adjacent scale member, and a key having an eye mounted on said rear rivet and engaging said openings of the body plate and bearing block. 35
8. A bearing for scales comprising a frame, a bearing block mounted on said frame and adapted to engage with a pivot pin of the scale, and an anti-friction device comprising a body plate arranged between the back of said block and the adjacent part of said frame, a lip arranged on the end of said body plate and extending across the end of said block, and a bearing nose projecting laterally from said lip and adapted to engage an adjacent member of the scale. 40
9. A bearing for scales comprising a frame, a bearing block mounted on said frame and adapted to engage with a pivot pin of the scale, and an anti-friction device comprising a body plate arranged between the back of said block and the adjacent part of said frame, a lip arranged on the end of said body plate and extending across the end of said block, and a bearing nose projecting laterally from said lip and adapted to engage an adjacent member of the scale. 45
10. A bearing for scales comprising a frame, a bearing block mounted on said frame and adapted to engage with a pivot pin of the scale, and an anti-friction device comprising a body plate arranged between the back of said block and the adjacent part of said frame, a lip arranged on the end of said body plate and extending across the end of said block, and a bearing nose projecting laterally from said lip and adapted to engage an adjacent member of the scale. 50
